UNITED STATES PATENT OFFICE.

WILLIAM CHRISTIAN STOWE, OF STEILACOOM, WASHINGTON.

TOOL HANDLE.

Application filed June 10, 1921, Serial No. 476,602. Renewed April 20, 1926.

This invention relates to an improved device for protecting handles of tools from splitting, splintering, or wearing adjacent their connection with a work element.

5 Specifically, the invention includes a protecting wedge member for mounting about a handle, and adapted for insertion into the handle aperture of a work element, such as an axe blade, hatchet blade, pick or the like.

A further object of the invention is the provision of a device of the above described character, which includes protecting members of novel formation to snugly engage the 15 sides of a tool handle, and for maintaining a work element secured to said handle; allowing for shrinkage, or decreasing size in the handle, by a wedging action.

Other objects and advantages will be apparent during the course of the following detailed description.

In the accompanying drawing, forming a part of this specification, and in which similar reference characters designate corresponding parts throughout the several views,

25 Figure 1 is a fragmentary side elevation of an axe handle and blade, showing the improved protecting means mounted thereon.

Figure 2 is a cross sectional view taken 30 on the line 2—2 of Figure 1.

Figure 3 is a central vertical section taken on the line 3—3 of Figure 1.

Figure 4 is a transverse cross section taken on the line 4—4 of Figure 1.

35 Figure 5 is a transverse cross sectional view taken on the line 5—5 of Figure 1.

Figure 6 is an enlarged fragmentary side elevation of a detail of the protecting device.

In the drawing, wherein for the purpose 40 of illustration is shown a preferred embodiment of my invention, the letter A designates a tool handle for use upon a working element B. Protecting means C is provided for engagement about the handle A, to maintain the working element B in rigid position 45 thereon for protection purposes; the retaining means D being provided as part of the protecting device.

The handle A can of course be of any approved type, such as the type now in standard use, and depending upon the implement upon which used. The handle A generally includes the tapered blade receiving end 10. The working element B can, of course, be an axe blade, pick, or similar working tool, having the substantially oval shaped aperture

or handle receiving opening 11 therein. It is preferred, that the tapered end 10 of the handle, be substantially oval in formation, tapering upwardly for reception within the 60 opening 11 of the working element B; the sides of the tapered end 10 designated by the major axis of said end, being substantially flat as at 12, and 13, for reception of a portion of the protecting means C. In this 65 manner, when the tapered end 10 is inserted in the blade B, independent of the protecting means C, substantially segmental shaped openings are provided in the aperture or opening 11, adjacent the flat sides 12 and 13. 70

The protecting means C preferably comprises a pair of strips 14 and 15, adapted for overlying the tapered sides 12 and 13 of the end 10, of handle A. The strips 14 and 15 are substantially similar in formation, including a substantially U-shaped body 16 to provide a pocket for receiving the sides of the end 10 of a handle. It is preferred that the socket shaped portions 16 be relatively thick at their bight portions; 80 the thickness of said bight portion gradually diminishing outwardly into the sides 17 and 18.

The end 10 of the handle A is substantially oval in formation, and in this event 85 the strips 14 and 15 may be disposed upon the opposite sides intersected by the major axis of said oval shaped end. The protecting strips 14 and 15, are each provided with a reduced upwardly extending shank 90 19, substantially segmental in cross section, for overlying the flat ends 12 and 13, of the end 10, to complete the line of oval formation of said end 10, as is clearly shown in Figure 2 of the drawing. Both of the strips 95 14 and 15, are provided with outwardly extending heads 20, upwardly upon the reduced shanks 19; the heads 20 projecting outwardly from the strips 14 and 15, and in direction opposite the extending sides 17 and 18.

The retaining means D, is of novel formation, and adapted for maintaining the strips 14 and 15 in snug adjustable relation of the handle A, below and exteriorly of 105 the work element B. The strip 15, is preferably provided adjacent its lower end 21 with the laterally extending fingers 22. The fingers 22, are of similar formation, and disposed upon the sides 17 and 18, for 110 overlying opposite sides of a handle A. Each finger 22 includes a shank 23, and an

enlarged beveled head 24, provided with outwardly extending shoulders 25 at the point of connection of the shank 23 and head 24.

6 The strip 14, is provided with co-operating outwardly extending portions 26. The extending portions 26 are mounted upon the sides 17 and 18, adjacent the end of the body portion 16, opposite to the shank 19. Each 10 extension 26 is provided with a pocket 27, having the inclined and converging dove-tailed grooves 28 therein, converging away from the U-shaped portion 16 of the strip 14. A passageway 29 is provided outwardly on each extension 26, for the reception of a shank 23, of a finger 22. By the above described means, the strips 14 and 15 can be maintained in adjustable detachable arrangement; the beveled heads 24, engaging in the beveled grooves 28 of the pockets 27, in dove tailed arrangement.

In assembling the improved protecting handle means, the strips 14 and 15 are first disposed upon the smaller portion of the 25 handle A, and slipped upwardly into place on the tapered end 10. When approaching the tapered end 10, the side of said end 10 will engage in the channel shaped portion 16 of the strips 14 and 15, and force said strips outwardly with respect to each other. This will have the effect of engaging the head 24 of each finger 22 in a pocket 27, until the abrupt shoulders 25 of each of the fingers 22 approach into proximate position with the abrupt shoulders 30, adjacent the formation of the passageway 29 into the pocket 27. The blade or working element B, is then slipped over the handle A and onto the shanks 19 of the strips 14 and 15. 40 In this position, the work element B will engage the shank 19, as well as the side portions of the tapered end 10, which remain free of any portion of the protecting means C. It should be noted in this connection, 45 that the channel shaped portion 16 of the strip will lie downwardly of the work element B, and outside of the handle aperture 11. As the tapered end 10 is then forcibly drawn into the strips 14 and 15, said strips will be braced or expanded, and the shank 19 thereof will bite into the interior of the opening 11, to engage the work element B. In this position, the overlying heads 20 will project upon the top of the work element B, and prevent any liability of the work element B slipping over the protecting strips 14 and 15.

Should the handle tapered end 10 shrink to any appreciable degree, the same will be forced downwardly in the means C by use 60 of the tool, and will have the effect of working the shank 19 into contact with the work element B.

From the foregoing, it can be seen that a protecting device has been perfected, 65 which will prevent splintering of the tapered end 10 of the handle A, while at the same time acting as an effective retaining means for securing the work element B on the handle A. It is preferred that the strips 70 14 and 15 be manufactured of some durable material, preferably metal, and having the retaining means D accurately developed to permit of wedge expansion of the strips 14 and 15, while retaining them in effective 75 working relation.

Various changes in the shape, size and arrangement of parts may be made to the form of the invention herein shown and scribed, 80 without departing from the spirit of the invention or the scope of the claim.

I claim:

A tool comprising a head having a socket formed therethrough, a handle having a portion extending through the socket of said head and a tapered portion adjacent the socket engaging portion, strips extending through the socket between the handle and end walls of the socket, the strips beyond the inner end of the tool head being curved 90 transversely and straddling opposite sides of the tapered portion of the handle, arms extending from opposite sides of the inner end portion of one of said strips and having recesses leading inwardly from their free ends and provided with parallel side walls for a portion of its length and being then enlarged to provide abutment shoulders, the side walls of the enlarged portion 95 extending inwardly in diverging relation and having a portion offset to provide a second set of abutment shoulders, the portion between the first and last mentioned shoulders being undercut, and arms extending from the opposite sides of the inner end portion of the other strip and extending in 100 overlapping relation to the first mentioned arms and into the recesses thereof and shaped to conform to the contour of the recesses and to engage the shoulders and fit beneath the undercut side portions and securely hold the strips in place about the handle.

WILLIAM CHRISTIAN STOWE.
